Primary Examiner — Patricia A Palasik*(74) Attorney, Agent, or Firm* — Notaro, Michalos & Zaccaria P.C.(57) **CLAIM**

The ornamental design for an eight channel pipetting arm, as shown and described.

DESCRIPTION

FIG. 1 is a front, bottom, left perspective view of an eight channel pipetting arm showing our design therefor;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a left, top, rear perspective view thereof.

The broken lines in the drawings depict portions of the eight channel pipetting arm and form no part of the claimed design.
